(57) **CLAIM**

(**) Term: **14 Years**

The ornamental design for a two-piece rifle scope mount adapter, as shown and described.

(21) Appl. No.: **29/168,780**

DESCRIPTION

(22) Filed: **Oct. 9, 2002**

FIG. 1 is a perspective view of a two-piece rifle scope mount adapter showing our new design.

(51) LOC (7) Cl. **22-01**

FIG. 2 is a plan view of one-half of the adapter, the other half being an identical half.

(52) U.S. Cl. **D22/110**

FIG. 3 is a bottom view of the adapter half.

(58) Field of Search D22/100, 108,

D22/109, 110, 199; 42/98, 113, 116, 119,

124, 125, 127; 33/533, 645

FIG. 4 is a left side elevation view of the adapter half.

(56) **References Cited**

FIG. 5 is a right side elevation view of the adapter half.

U.S. PATENT DOCUMENTS

FIG. 6 is a front elevation view of the adapter half; and,

FIG. 7 is a rear elevation view of the adapter half.
